(57) **CLAIM**

The ornamental design for a graphical user interface for a server maintenance tool for a computer display, as shown and described.

DESCRIPTION

The sole FIGURE is a front view of a computer display for a server maintenance tool with graphical user interface showing our new design.

The perimeters of the underlying computer display screen are understood to be flush.

The broken line showing of the text is for the purpose of illustrating environment and forms no part of the claimed design.
